UNITED STATES PATENT OFFICE.

CARL J. SCHWARZE, OF ADRIAN, MICHIGAN, ASSIGNOR TO SCHWARZE ELECTRIC COMPANY, OF ADRIAN, MICHIGAN, A CORPORATION OF MICHIGAN.

ELECTROMAGNETICALLY-OPERATED SOUNDER.

1,092,117.

Specification of Letters Patent. Patented Mar. 31, 1914.

Application filed October 13, 1910. Serial No. 586,848.

To all whom it may concern:

Be it known that I, CARL J. SCHWARZE, a citizen of the United States of America, residing at Adrian, in the county of Lenawee and State of Michigan, have invented certain new and useful Improvements in Electromagnetically-Operated Sounders, of which the following is a specification, reference being had therein to the accompanying drawings.

The invention relates to sounders or audible alarm devices, and has more particular reference to constructions in which the sound is produced by an electromagnetically vibrated member.

It is the object of the invention to obtain a loud sounding alarm which may be operated by comparatively small battery power, further to obtain a compact, simple and inexpensive construction, further to avoid sparking of the make and break electrodes, and still further to secure advantages more fully hereinafter set forth.

In the drawings.—Figure 1 is a central longitudinal section through the sounder; Fig. 2 is a plan view thereof with the cap removed; Fig. 3 is a diagram illustrating the connection and arrangement of the electric circuits. Fig. 4 is a fragmentary sectional view showing the manner in which the binding posts secure the cap to the casing.

A is a casing preferably of circular form and having at opposite ends thereof the caps B and C.

D is a metallic diaphragm stretched across the casing adjacent to the cap B and secured at the margin by clamping between flanges E and E² respectively of the casing A and cap B by bolts F.

G is an iron plate parallel to but spaced from the diaphragm D by a gasket E' and secured by the bolts F.

H are magnetic core pieces secured to the plate G and in connection therewith forming a multi-pole horseshoe electric magnet. As shown, there are four cores H each of which is surrounded by a coil I of insulating wire. In the center of the plate G is an apertured bearing J preferably of a non-magnetic metal in which a vibratory stem K is secured. The stem K has mounted thereon a disk L which forms an armature for the magnet.

M is a circuit breaker formed by a metallic plate of resilient material secured at its

outer end to the casing A and bifurcated at its inner end to embrace the stem K.

N is a collar on the stem for engaging the bifurcation of the member M.

O is a contact mounted on the member M, 60 and P is an adjustable contact point mounted on a support Q and coöperating with the contact O. R is a spring secured to the casing A and extending into the path of the end of the stem K.

The electric connections for the sounder are formed through terminal posts S which also form the mechanical means of securing the cap C to the casing A but which are electrically insulated therefrom. As shown 70

in Fig. 4, the posts S extend through the cap C and engage lugs S' extending inward in the upper end of the casing. The binding post S is insulated from the cap C by insulation S² and from the casing A by insulation S³.

From these terminals, connection is made through conductor T to the contact P, while the opposite terminal is connected by a conductor T' to the coils I from which the circuit leads to the contact O 80

on the vibrator M. Thus when the circuit is closed the magnets will be energized attracting the disk armature L and causing the stem K to deliver a blow against the diaphragm D. This movement will cause the collar N to flex the member M withdrawing the contact O from the coöperating contact P and opening the circuit which by deenergizing the magnet, permits the stem K and armature L to be thrown backward by the 90

recoil of the diaphragm D. In this return movement, the stem is moved into contact with the spring R which forms a yieldable buffer overcoming the inertia of the moving parts.

The rapid opening and closing of the electric circuit of a magnet will cause the generation of a spark at the separated electrodes. This I have avoided to a large extent by providing each of the magnet cores with an additional coil U which is short circuited and serves to discharge the induced current which otherwise would pass through the spark cap. Spark difficulties are still further guarded against by the use of a 100 condenser having the opposite inductors thereof connected respectively with the contacts O and P. This condenser I preferably construct in cylindrical form and preferably by adjacent insulated wires V and V' which 110

are coiled adjacent to the inner face of the casing, being wound upon a spool W.

- In operation, whenever the circuit is closed a very rapid vibratory movement is imparted to the armature and stem, causing the latter to strike against the diaphragm D and thereby generate the sound. The resiliency of the diaphragm will cause the recoil of the stem and armature, and the amplitude of the vibratory movement will vary in accordance to variations in speed. Thus in starting, the armature may only move far enough in its return movement to cause the closing of the electric circuit through the contacts O and P, but when full speed is acquired (which is almost instantaneous) the inertia of the moving parts will further deflect the spring R, increasing the amplitude of vibration.
- 20 For intensifying the sound, the cap B is preferably formed with a nipple X which may be attached to a horn or megaphone.

What I claim as my invention is:

1. The combination with a casing, of a diaphragm extending thereacross, a reciprocating rod adapted to impinge against said diaphragm and extending perpendicular thereto and centrally thereof, a bearing in which said rod is slidably secured, a disk armature on said rod, and an electromagnet having a plurality of poles concentric with the axis of said rod and exerting a balanced pull on said armature in a direction toward said diaphragm, a spring for retracting said rod, a make and break circuit closer actuated by said rod and controlling said magnet, and a buffer spring at the opposite end of said rod.
2. The combination with a casing, of a diaphragm extending thereacross, an electromagnet arranged within said casing and having a plurality of poles concentric with the axis thereof, a bearing in the center of said casing, a reciprocating rod slidably secured in said bearing and adapted to impinge against said diaphragm, a disk armature mounted on said rod, a spring for

retracting said rod, a make and break circuit closer coöperating with said spring and controlling said magnet and a buffer for the opposite end of said rod. 50

3. The combination with a reciprocating member and electro-magnetic means for initially moving said reciprocating member, of resilient members for respectively rebounding said reciprocating member upon movement in either direction, one of said resilient members being a disk sound producer and the initial movement of said reciprocating member being independent of both of said 60 resilient members. 55

4. The combination with a resilient disk sound producer of a resilient buffer, a reciprocating member movable therebetween and having its movement in one direction yieldably limited by said sound producer and its movement in the opposite direction yieldably limited by said resilient buffer, and electro-magnetic means for initially impinging said reciprocating member against said 70 resilient sound producer, the initial movement of said reciprocating member being independent of said resilient buffer. 65

5. The combination with a resilient diaphragm, of a resilient buffer opposed thereto, a striker substantially freely movable therebetween having its movement in one direction yieldably limited by said resilient diaphragm and its movement in the opposite direction yieldably limited by said resilient 80 buffer, an armature in operative relation to said striker, an electro-magnet for controlling said armature to initially impinge said striker against said resilient sound producer, and a relatively light spring for holding 85 said armature in normal position, the initial movement of said striker being independent of said buffer. 75

In testimony whereof I affix my signature in presence of two witnesses.

CARL J. SCHWARZE.
